UNITED STATES PATENT OFFICE.

CHARLES APELT, OF COMFORT, TEXAS.

DESIGN FOR A LAMP SHADE.

Application filed October 6, 1928. Serial No. 28,389. Term of patent 7 years.

To all whom it may concern:

Be it known that I, CHARLES APELT, a citizen of the United States of America, and a resident of Comfort, in the county of Kendall and State of Texas, have invented a new, original, and ornamental Design for a Lamp Shade, of which the following is a specification, reference being had to the accompanying drawing, forming part thereof.

The figure is a perspective view of a lamp shade, showing my new design.

I claim:

The ornamental design for a lamp shade, as shown.

CHARLES APELT.
